UNITED STATES PATENT OFFICE

143,735

DESIGN FOR A MEDAL

Harvey Michael Keiper, Frackville, Pa.

Application April 3, 1945, Serial No. 118,841

Term of patent 3½ years

(Cl. D29—19)

To all whom it may concern:

Be it known that I, Harvey Michael Keiper, a citizen of the United States, residing at Frackville, in the county of Schuylkill and State of Pennsylvania, have invented a new, original, and ornamental Design for Medals, of which the following is a specification, reference being had to the accompanying drawing, forming part thereof.

Fig. 1 is a front view of a medal showing one face of the duplicate faces of my new design.

Fig. 2 is a side view thereof.

I claim:

The ornamental design for a medal, as shown and described.

HARVEY MICHAEL KEIPER.
